METHOD OF FILLING CONTAINERS WITH
EXPLOSIVE MIXTURES

Nevil Monroe Hopkins, New York, N. Y.; Raymonde B. Hopkins, executor of said Nevil Monroe Hopkins, deceased

Application March 9, 1942, Serial No. 433,988

7 Claims. (Cl. 86—20)

This invention pertains to the practically perfect and safe making of a fluid explosive, one safer to package, ship, store and use after making and packaging, than such explosives as dynamite or nitroglycerin, for example.

It is an object of this invention, therefore, to provide not only practically perfect safety in the making and packaging of an explosive, but to produce a packaged explosive as an article of manufacture, safer to ship, store, and use than dynamite or nitroglycerin, for example.

It is a particular object of this invention to package, with the highest degree of safety to life, limb and property, nitrogen tetroxide and one or more liquid, semi-liquid, or solid combustible bodies, benzol, ordinary gasoline, high octane gasoline, kerosene, carbon-disulphide, turpentine, certain heavy greases, and certain finely divided combustible solids and the like, to use as a substantially safe explosive cartridge or cannister as compared to such explosives as dynamite and nitroglycerin, for example.

It is also a special object of this invention to institute a greater element of safety than heretofore to life, limb and property in the preparation of the explosive as in the preparation of nitroglycerin and dynamite, due to the fact that the explosive herein described is not produced until after it has been packaged and the mechanical process of hermetic sealing has been completed.

Liquid nitrogen tetroxide, when mixed with a liquid combustible body such as benzol, for example, enters into a mutual solution therewith, no conventional chemical reaction with the evolution of heat taking place as in the case of nitrating glycerin, for example; therefore all the potential energy present in the component parts of the explosive is packaged for the blast at the field of use. In nitrating glycerin, the reacting masses must be kept cool by running water and naturally many thermal units of energy are discarded in the process of manufacture. Since there are no comparable thermal units thrown away in making a mere mutual solution of liquid nitrogen tetroxide and benzol, for example, applicant asks the question, Why throw away at the factory what you wish to use in the field?

In order to adequately introduce this subject, 50 setting forth thereby the needs for the new products proposed, a brief résumé of the characteristics of two liquid, and several solid explosives is given, and applicant's reasons, who has been engaged in explosives, for over forty years, where-

in they all fail in connection with industrial and military use.

Nitroglycerin is too sensitive to shock and therefore too dangerous. Furthermore if nitroglycerin leaks out of a container it may form dangerous pools or puddles, which is not the case with cartridges and cannisters using liquid nitrogen tetroxide as one of the component parts. Moreover, nitroglycerin has far too great a shattering power 10 for some purposes, and freezes at 13.1° C. or 55.5° F.—a comparatively high temperature. Moreover, nitroglycerin is a dangerous compound to thaw out when frozen. In addition, it causes severe headache when it comes in contact with the 15 skin.

Dynamite is also too sensitive to shock and likewise too dangerous for most industrial purposes, and is not favored for any military or naval purposes, not only because it is easily frozen, 20 since it has a nitroglycerin content and is dangerous to thaw out, but it is readily detonated by a comparatively light shock, and usually by the impact of a rifle bullet. Moreover, the safe storage period for dynamite is limited.

25 Liquid oxygen is applied as an explosive in mines when mixed with charcoal where prompt firing of the charge is possible. The liquid oxygen must be transported to the mines in open vessels, the liquid boiling off continually and therefore 30 always at considerable loss, since liquid oxygen cannot be confined practicably by hermetic sealing. Liquid air explosives, however, possess a very desirable safety factor, due to the very fact that after a period of time, if a charge is not fired, it 35 boils away, and leaves a harmless deposit of carbonaceous material behind. Thus many accidents which occur with dynamite which has failed to explode in a bore hole and subsequently accidentally detonated, are avoided. Due to the fact, however, that liquid oxygen cannot be hermetically sealed, its use as an oxidant as a component part of an explosive mixture is very limited.

40 Ammonium nitrate dynamite is manufactured under a number of formulas and trade names, and contains usually from 20 to 30 per cent nitroglycerin. It is quite hygroscopic, and is too dangerous for most purposes, especially military demolition work, as it is also detonated by the impact of certain rifle bullets or flying shell fragments.

45 Ammonal is another ammonium nitrate explosive, very hygroscopic and lacks proper shattering power for many purposes.

Ammonium picrate is far too insensitive for 55 blasting and military demolition work, since it

requires an expensive high shock booster detonation to set it off.

Blasting gelatin is made according to a variety of formulas. It occasions very severe headaches when it comes into contact with the hands of the human body, and is again too sensitive to shock for many purposes.

Picric acid is a nitrated phenol and is an ill and uncertain explosive. It becomes wet in the atmosphere and is set off when in this condition with great difficulty. It is crumbly and porous, and not only stains the skin and clothing, but it forms dangerously sensitive salts when in contact with certain metals. The nitration process is a roundabout and uneconomic one.

Gun cotton has to be kept wet to prevent it from undergoing chemical change and in becoming too sensitive. When it is wet it requires dry gun cotton, or an equivalent high-power booster, to cause its detonation.

Nitrostarch more or less recently developed for demolition purposes, by the military engineers, is not very stable and accelerated stability tests, as well as long periods of storage, have not shown it to be wholly reliable. It is quite hygroscopic and not very effective in producing induced detonation.

T. N. T. is far too expensive for industrial blasting and in addition it requires a high power booster detonator to set it off. It has been standardized practically the world over for military and naval purposes, but is dependent upon toluene, a commodity which may become very difficult to procure in large enough quantities during a prolonged major war.

Amatol is a mixture of T. N. T. and ammonium nitrate and although somewhat cheaper than T. N. T. is still too expensive for industrial blasting purposes.

With the foregoing enumerated objects in view, as well as certain other objects which will become apparent as the description proceeds and the drawings are studied, the invention consists in the improvements over the prior art as partially listed above, and consists in the novel parts and principles, methods, ways and means, as well as physical states of matter, all as herein set forth, and particularly pointed out in the claims.

Referring to the accompanying drawing forming a part of this specification, in which like numerals designate like parts in all the views:

Fig. 1 is a sectional view through one design of one of my completed articles of manufacture, comprising an explosive cannister with a cap supported well-way, showing in elevation an electrical detonator therein positioned to fire the cannister-contained explosive charge.

Fig. 2 is a sectional view through one design of one of my articles of manufacture, showing alternate detail plans for a detonator well-way, and recess, respectively, and one of the liquid component parts of the liquid explosive in the liquid state, and another of the liquid component parts of the said liquid explosive in the frozen solid state.

Fig. 3 represents one design of one of my double-safe and easily vented cartridges, comparable in size and shape to a conventional dynamite cartridge. The contained component parts of the liquid explosive are adjusted for a given sensitivity in strength, with one of the liquid component parts of the liquid explosive, namely the nitrogen tetraoxide, frozen solid as evidenced by the oblique cross hatching of comparatively widely separated lines.

Fig. 4 represents a similar design of one of my cartridges with one of the liquid component parts of the liquid explosive, namely the nitrogen tetraoxide, frozen solid as evidenced by the oblique cross hatching of comparatively widely separated lines, this cartridge having a greater sensitivity in strength over that illustrated in Figure 3.

Referring to Fig. 1 20 is a cannister wall of sheet iron, sheet tinned iron, sheet steel, or aluminum, for example, of definite gauge and thickness, and of definite characteristics as to hardness and thickness, for example, 21 indicating a bottom member, either integral with the side walls of the cannister as by deep drawing, or attached by one of the standard mechanical closure methods in can manufacture with a gas and liquid tight juncture, and 22 is a cap member, mechanically applied to the top of the cannister to make a pressure resisting, as well as a gas and liquid tight, fit. The cap may be of the well-known crown cap and seal variety, such as is used on beer, gingerale and charged water bottles, in which case the lip member 23 of the neck 24 must be crimped or beaded to receive it, no attempt being made in the drawing to show the well-known corrugated elements of such a crown cap and seal. In the place of the crown cap, I may of course elect to use a threaded cap and a threaded neck member, using the inexpensive rolled threads, for example, or make a soldered cap closure, using a pure tin or lead-free solder, since liquid nitrogen tetraoxide attacks lead but does not attack tin at all ordinary temperatures. I may in the top of this cap member 22 bore a countersink, 200, thereby reducing the thickness of the metal there so that it may be easily punctured, by a needle-pointed bradawl, in order that vapor from the surface 300 of the mixed liquid explosive 50 may escape, and in due time, a time which may be adjustable with temperature, and thus render the explosive cannister harmless, if the charge is not fired within an adjusted or specified time.

Here supported from the cap member 22 is a detonator well-way 25, either a deep drawn and integral part of the cap, or mechanically attached with a pressure resisting gas and liquid tight joint. 26 illustrates in elevation an electric detonator, and 27 and 28 are insulated electric wires connected to a heating bridge wire within the detonator casing and adjacent to the fulminating mercury or other explosive capable of being exploded by heat. Here 50 is an explosive mixture of liquid nitrogen tetraoxide and one or more combustible bodies, benzene, gasoline, especially high octane gasoline for anti-freeze purposes, kerosene, carbon disulphide, heavy grease, heavy grease incorporated with finely divided carbonaceous matter, or the like. This explosive mutual solution or mixture, or both, may be one of many, ranging from one consisting of 20 per cent liquid nitrogen tetraoxide to 80 per cent of benzol by volume, for example, to one consisting of 70 per cent liquid nitrogen tetraoxide to 30 per cent benzol by volume, for example, the exact proportions of such mixtures being dictated by sensitivity or power to do work requirements.

In Fig. 2 in a wall of the cannister 20 is shown an alternate well-way or recess 31 for the reception of a detonator and the additional alternate well-way 25' integral with, as by deep drawing, or mechanically and hermetically attached against internal pressure to the bottom or closure member 21'. In this view a simple closure cap

22' has been forced upon the bead 23' said simple cap being bored part way through at 200 in order that a pointed bradawl may easily perforate the metal over the gas chamber formed by the neck of the cannister above the liquid level 300. In the place of the simple crown cap of course a simple screw cap or other suitable closure system may be mechanically, as well as hermetically, applied. In the filling operation, a volume of liquid nitrogen tetraoxide is supplied to the interior of the can, and then frozen therein, as indicated by the cross hatched lines at 40, and this freezing operation may be carried out by immersing the cannister in a suitable freezing mixture, or by immersing the cannister in a trough of flowing brine, said brine being an element of a mechanical refrigerating system. Since liquid nitrogen tetraoxide freezes at minus ten degrees Centigrade or 14 degrees Fahrenheit, to a mass of colorless crystals, there is no difficulty at all in not only freezing the liquid gas to a solid, but in super-cooling the frozen mass. Here 30 is a volume of refrigerated benzol, or a volume of refrigerated benzol to which a freezing point depressant has been added, some high octane gasoline for example, so that the benzol will not freeze above the temperature of the liquid nitrogen tetraoxide, but be liquid at the same temperature, or lower. This to prevent the melting of the solid frozen nitrogen tetraoxide and consequent mixing with the benzol, and thereby making a partial or complete explosive mixture therewith, until completion of the mechanical process of forcing on, or screwing on, or soldering, or otherwise attaching the cap member 22'.

By this novel means of filling the cannister with nitrogen tetraoxide and one or more liquid combustible bodies, the said nitrogen tetraoxide being in frozen state to prevent its admixture with the liquid body, I insure the highest order of safety in packaging to life, limb and property, no matter how roughly the cannister is handled or how sharply the cap member may be forced on by hand, by semi-automatic, or by automatic machinery. In the present illustration, it will be evident that upon thawing out the frozen component of the fluid explosive, that we will have substantially a 50-50 mixture by volume of the liquid nitrogen tetraoxide and the liquid hydrocarbon or hydrocarbons respectively.

In the new filling process involving this principle for the highest order of safety, I plan to advance step by step a plurality of my open mouthed cartridges or cannisters suitably supported upon a moving belt, said moving belt advancing step by step while immersed in a trough of refrigerated brine, said brine being at a temperature well below the freezing point of liquid nitrogen tetraoxide. During the step by step process the cartridge cases or cannisters are passed successively under suitable nozzles leading to refrigerated, but not frozen, supplies of liquid nitrogen tetracoxide and liquid or fluid combustible substances respectively. At refrigerating temperatures of just above the freezing point of liquid nitrogen tetraoxide, the liquid gas is docile and easily and safely handled, a suitable exhaust fan system being nevertheless installed to carry off and discharge out of doors any nitrogen-tetraoxide-vapor-contaminated atmosphere. After the cannisters have been filled to the required depth, according to the sensitivity and power of the explosive desired, and the said liquid nitrogen tetraoxide frozen solid, the refrigerated benzol,

gasolene, or mixture of benzol and high octane gasolene, for example, is then admitted through suitable nozzles to fill the cartridges or cannisters except for a suitable liquid-free space to serve as a gas chamber as indicated in the drawing.

After the addition of the refrigerated liquid hydrocarbon or hydrocarbon mixture, the cartridges or cannisters are passed under the cap-applying mechanism. With continuous indication of brine temperature by suitable recording thermometers taken in connection with the time of immersion of the cartridges or cannisters in the brine during their advancements through the brine in the filling process, we may always know that one or all of the component parts of the liquid explosive are frozen solid and moreover that the liquid nitrogen tetraoxide, because of its freezing point, was frozen first, and therefore there would be the minimum of danger to life, limb, and property under the capping machinery. It is not deemed necessary to illustrate here the complete intermittent motor drive of the endless conveyer belt nor the details of the trough and the immersion of the belt therein, nor the measuring devices at the filling nozzles, nor any of the other numerous details necessary and standardized in more or less analogous automatic filling systems, the filling of beer cans and bottles with beer, for example.

Coming now to Fig. 3, there is shown at 60 a simplified cap member with a drawn well-way 61 for the reception of the firing detonator and a miniature drawn well-way 61' one drawn by dies fashioned to produce a thin and easily punctured bottom. Both of these well-ways project downward from the cap member 60, which is attached to an end 62 of the iron, tinned iron, steel or aluminum shell 63, by screw threads and gasket (not shown), by a drive fit and soldering using lead-free tin solder, by rolling on, by welding, or any other pressure resisting and gas tight method or ways and means.

Here the miniature well-way 61' has a thinned bottom member 200', one easily punctured by a bradawl with needle point, which puncture upon the removal of the bradawl allows the vapor of the liquid nitrogen tetraoxide at the surface level 300' to escape. I may elect to supply the interior of this miniature well-way 61' with a standardized needle-point 400 attached to a small friction-guiding spider 500, said needle point being ground upon a shaft which extends slightly above the cap 60 and terminates in a button 600 fashioned to be depressed by the thumb of the operator. By standardizing the thickness of the metal at 200' and the ogive and diameter of the steel needle for puncturing, I may be able to calibrate for definite periods of time for the complete escape of the liquid nitrogen tetraoxide after puncturing the bottom end 200' of the well-way 61' when the cartridges are at the temperature of melting ice, for example, easily attained by putting a dozen or more of these new blasting cartridges in a bucket of ice and water.

By means of this method it will be evident that these cartridges may be rendered safe within substantially the same period of time in either summer or winter. Where numerous holes have been drilled in rock or made in soil, for example, and a plurality of cartridges are planted for a blast, only one of the cartridges being fired by a detonator, it frequently happens that all of the cartridges are not fired by sympathetic detonation, in which case, with ordinary dynamite cartridges, serious accidents to life and limb may

subsequently result from an unfired cartridge. With the present cartridge, if one or more should fail to fire by sympathetic detonation, they will be rendered harmless after a preadjustment period of time, because the liquid nitrogen tetraoxide will boil away, its vapor passing through the calibrated hole made by the needle in the metal bottom 290' of the well-way 61'. The cartridge shown at Fig. 3 has a bottom closure member 64 attached to the end 65 of the shell 63, the attachment being made pressure resisting and gas and liquid tight.

Here, as in the case of the cannisters of the previous figures, 40 is a mass of frozen nitrogen tetraoxide, and 30 a volume of a refrigerated liquid hydrocarbon or a mixture of refrigerated liquid hydrocarbons, or other combustible material with a temperature as low as or lower than the temperature of the frozen solid nitrogen tetraoxide. Here we have a substantially 50-50 volume respectively of the combustible material and the solid frozen liquid gas, capped and sealed hermetically before the frozen solid liquid gas has had time to melt and mix with the liquid combustible material. This 50-50 mixture of chemically controlled ingredients, when they are both in the fluid state, may be tested according to applicant's standardized kinetic energy impacts.

In Fig. 4 there is shown substantially the same structure as in Figure 3, only a different distribution of frozen liquid nitrogen tetraoxide and liquid combustible material, a mixture more sensitive to shock and also one more powerful when exploded, since high sensitivity and high power go largely hand in hand in the present liquid explosive. The cartridge casing here as before has been hermetically closed before the melting of the frozen nitrogen tetraoxide 40, thereby eliminating all danger to life, limb and property.

Though this invention has been particularly described in the foregoing as adaptable to explosive cartridges containing a liquid mixture of nitrogen tetraoxide and a combustible body such as a hydrocarbon (benzene for example), it is quite obvious that the invention is capable of application, in a broader sense, to an hermetically sealed container having therein a plurality of any ingredients (constituting a mixture) one of which ingredients is of such a character as would be vaporized, chemically changed, or actually ignited and/or exploded by the temperature necessary to complete the hermetic sealing of the container, and hence some of the claims have been directed to cover such broader aspect of the invention.

It is obvious that those skilled in the arts may vary the steps and combinations of steps constituting the novel method herein described without departing from the spirit of this invention, wherefore it is desired not to be limited to the exact foregoing disclosure except as may be required by the claims.

What is claimed is:

1. The method of filling a container with two liquid ingredients which comprises introducing one of the ingredients in a liquid phase thereof into the container, freezing the introduced liquid ingredient while in the container, introducing the other ingredient in a liquid phase thereof into the container and in contact with the frozen ingredient, hermetically sealing the container before the frozen ingredient has melted, and liquefying the frozen ingredient after the container is sealed.

2. The method of producing an explosive car-

tridge consisting of a container and a mixture therein of ingredients each separately relatively insensitive to explosion but forming a sensitive explosive mixture when admixed, which comprises disposing in the container one of the ingredients in a solid phase thereof, introducing the other ingredient in a liquid phase thereof into the container and in contact with the solid ingredient, maintaining the two ingredients in their relatively insensitive respective solid and liquid phases while hermetically sealing the container, and liquefying the solid phase ingredient after the container is sealed to bring about the admixture of both ingredients.

3. The method of producing an explosive cartridge consisting of a container and a mixture therein of liquid ingredients each separately relatively insensitive to explosion but forming a sensitive explosive mixture when admixed, which comprises introducing into and solidly freezing one of the liquid ingredients in the container, adding the other liquid ingredient to the solidly frozen ingredient in the container, maintaining the two ingredients in their relatively insensitive respective solid and liquid phases while hermetically sealing the container, and liquefying the solid phase ingredient after the container is sealed to bring about the admixture of both ingredients.

4. The method of safely producing an explosive cartridge consisting of a container and a mixture therein of liquid ingredients each separately incapable of explosion but forming a sensitive explosive mixture when admixed, which comprises introducing into and solidly freezing liquid nitrogen tetraoxide in the container, adding a liquid hydrocarbon to the solidly frozen ingredient in the container, maintaining the two ingredients in their respective solid and liquid phases while hermetically sealing the container, and liquefying the solid phase ingredient after the container is sealed to bring about the admixture of both ingredients.

5. The method of producing an explosive cartridge consisting of a container and a mixture therein of liquid ingredients each separately relatively insensitive to explosion but forming a sensitive explosive mixture when admixed, which comprises introducing into and solidly freezing one of the liquid ingredients in the container, adding the other liquid ingredient to the solidly frozen ingredient in the container, the such addition being at a temperature at least as low as the temperature of the frozen ingredient, maintaining the two ingredients in their relatively insensitive respective solid and liquid phases while hermetically sealing the container, and liquefying the solid phase ingredient after the container is sealed to bring about the admixture of both ingredients.

6. The method of producing an explosive cartridge consisting of a container and a mixture therein of liquid ingredients each separately incapable of explosion but forming a sensitive explosive mixture when admixed, which comprises introducing into and solidly freezing liquid nitrogen tetraoxide in the container, adding a liquid hydrocarbon to the solidly frozen ingredient in the container, the ingredients being in the relative proportion of 60% by volume of liquid nitrogen tetraoxide to 40% by volume of liquid hydrocarbon, maintaining the two ingredients in their respective solid and liquid phases while hermetically sealing the container, and liquefying the solid phase ingredient after the container is sealed to bring about the admixture of both ingredients.

sealed to bring about the admixture of both ingredients.

7. The method of producing an explosive cartridge consisting of a container and a mixture therein of liquid ingredients each separately incapable of explosion but forming a sensitive explosive mixture when admixed, which comprises introducing into and freezing liquid nitrogen tetraoxide in the container, adding a liquid hydrocarbon to the solidly frozen ingredient in

the container, the ingredients being in the relative proportion of 30%-70% by volume of liquid nitrogen tetraoxide to 70%-30% by volume of liquid hydrocarbon, maintaining the two ingredients in their respective solid and liquid phases while hermetically sealing the container, and liquefying the solid phase ingredient after the container is sealed to bring about the admixture of both ingredients.
